UNITED STATES PATENT OFFICE

FAY D. KINNEY, OF WENHAM, MASSACHUSETTS, ASSIGNOR TO UNITED SHOE MACHINERY CORPORATION, OF PATERSON, NEW JERSEY, A CORPORATION OF NEW JERSEY

MACHINE FOR APPLYING PRESSURE TO SHOES

Application filed February 5, 1929. Serial No. 337,674.

This invention relates to machines for applying pressure to shoes and is herein illustrated as embodied in a machine particularly adapted to apply pressure to the upturned 5 margin of an unvulcanized rubber sole in a zone extending around the lower portion of the upper of a lasted shoe.

In the manufacture of shoes having rubber soles which are vulcanized in place it is common to apply a foxing of unvulcanized rubber along the lower margin of the lasted shoe, to apply to the bottom of the shoe an unvulcanized rubber sole having a beveled margin which projects beyond the edge of 15 the bottom of the shoe, and then to lay the sole by pressing it against the bottom of the shoe, bending the beveled margin of the sole up around the edge of the bottom of the shoe and pressing the upwardly bent margin 20 against the foxing. It sometimes happens that the upwardly bent margin, and more particularly the upper edge thereof, is not pressed firmly into contact with the foxing during the sole laying operation, and, if it 25 is not so pressed, a satisfactory joint between the two will not be secured when the shoe is subsequently vulcanized. In order to ensure that the upper edge of the upwardly bent margin of the sole shall be pressed securely into place, it is customary, after the sole has 30 been laid in the manner which has been described above, to perform an additional pressing operation by hand upon the upturned margin of the sole by running a so-called 35 "stitching wheel" along the edge of the upturned margin to ensure that it shall be firmly pressed at all points—and particularly along its extreme edge—against the foxing. An object of the present invention is to provide a machine by which this hand operation 40 and similar pressing operations may be carried out.

According to one feature of the invention there is provided a sectional holder the sections of which are fastened together by a flexible member so that the holder may be caused to conform to the curves along the lower edge of a shoe, and a distensible member carried by the holder which may be distended by air or other fluid pressure to cause

pressure to be applied to the shoe. In the illustrated construction two substantially U-shaped sectional holders are provided, one for the rear part of the lower margin of the shoe and one for the forepart, the sections of each holder being fastened together by a flexible steel band, and each holder containing a hollow, distensible, rubber member which may be inflated at the proper time to apply pressure to the shoe. In the operation of the machine, one of the holders is first brought into contact with the rear part of the shoe in the locality of the upturned margin of the sole and the distensible member inflated; and then this holder is withdrawn 60 and the other holder caused to act similarly upon the forepart of the shoe.

This and other features of the invention including certain details of construction and combinations of parts will be described as 70 embodied in an illustrated machine and pointed out in the appended claims.

Referring now to the accompanying drawings:

Fig. 1 is a front view, partly in elevation and partly in section, of a machine in which the present invention is embodied, and

Fig. 2 is a plan view of the machine.

The machine comprises a flat bed or table 3 having rising from it a standard 5. Adjustably held by a set screw 7 in the upper end of the standard is a horizontal rod 9 to the outer end of which the stem 11 of a block 13 is adjustably fastened by a set screw 15, said block having depending from its under side two last pins 17 adapted to enter the usual sockets formed in the top of the last of a rubber shoe 100. The shoe, shown in dot-and-dash lines, has a foxing 200 and a sole 300, the margin of the sole having 25 been bent up, as has been described above, the line of its upper edge being indicated at 400. In order to press this upturned portion of the sole, and particularly the extreme upper portion thereof, against the sides of the shoe—in this case against the foxing—there are provided two substantially U-shaped holders indicated as a whole at A and B each containing a distensible rubber tube with closed ends.

Inasmuch as the two holders and their associated parts are substantially alike, only one of them will be described in detail. The holder A consists of seven sections comprising a base section 19 and side sections 21. 5 These sections, as best shown in Figure 2, are shaped so that they may be arranged in the general form of a U. Two flexible steel bands 23, 25, of which the band 23 is fastened to the base section 19 and three of the side sections 21 and the band 25 is fastened to the base section and the other three side sections, hold the sections together while permitting the legs of the U-shaped holder to 10 be moved toward and from each other. The sections of the holder are flat on their bottoms and rest upon the table 3.

In order to move the holder A toward and from the shoe 100 as well as to open and 20 close the holder by swinging the legs thereof, the base section 19 is fast to one end of a rod 27 which is slidable in a horizontal bore in the standard 5. To the other end of the rod are pivoted at 29 the inner ends of two arms 25 31, 32. The outer end of the arm 31 is pivoted at 33 to one end of a slide rod 35 the other end of which is pivoted at 37 to one end of a link 39, the other end of said link being pivoted at 41 to an ear 43 formed on 30 one of the side sections 21 at the end of one of the legs of the U-shaped holder. The outer end of the other arm 32 is connected in a similar manner to the side section 21 at the end of the other leg of the holder by 35 means of a slide rod 45, a link 47 and an ear 49. Pivoted respectively to the arms 31 and 32 are the inner ends of links 51, 53, the outer ends of which are pivoted to a block 55 which is slidable transversely of the axis of the rod 27 in a horizontal guideway formed in the upper portion of an upright arm 57, the block being held in the guideway by plates 59. The hub of this arm has a square hole to receive a square rod 61 and is firmly fastened 40 to the rod by dowel pins 63 and a nut 65 which is threaded upon a reduced end of the rod. This rod is slidably mounted in grooves formed in the undersides of lugs 67, 69 which are rigid with the table 3 and is held in the 45 grooves by plates 71 fastened by screws 73. Formed on the under side of the rod 61 is a rack 64 with which meshes a pinion 66 fast to a rock-shaft 68, said rock shaft being 50 rotatable in brackets, one of which is shown 55 at 70, carried by the table 3. Pinned to the outer end of the shaft is the hub of a handle 72 by which the shaft 68 may be rocked.

With this construction the U-shaped holder A will be moved away from the rear part of 50 the shoe 100 and its legs swung apart when the shaft 68 is rocked in a direction to move the slide rod 61 to the left (Fig. 1); and when later the slide rod is moved to the right to move the holder A into operative relation to 55 another shoe, the base of the holder will first

contact with the rear end of the shoe and then the legs of the holder will swing toward each other to cause the holder to close about the sides of the rear part of the shoe. It should be particularly noted that the links, 70 arms and rods which connect the ends of the legs of the U-shaped holder to the reciprocating rod 61 form an equalizing device so that right and left shoes, as well as shoes of different styles will be properly engaged by 75 the holder.

The holder B, which is designed to extend around the forepart of the shoe, is substantially like the holder A and will not be described in detail. This holder, like the holder 80 A, is made up of sections 119, 121, fastened together by flexible steel bands 123, 125. Its base member 119 is fast to a rod 127, which corresponds to the rod 27 of the holder A, and is connected to a slide rod 161 (Fig. 1) in the same manner as the rod 27 is connected to the rod 61. The links 139, 147 correspond to the links 39, 47; the slide rods 135, 145 correspond to the slide rods 35 and 45; and these rods are connected to the slide rod 161 90 by means of arms and links like the corresponding arms and links which connect the slide rods 35 and 45 with the slide rod 61. This slide rod 161 is operated in the same manner as is the slide rod 61 by means of a 95 rack and pinion and a handle which are like the rack 64 the pinion 66 and the handle 72. In the operation of the machine, one of the holders, for example A, is moved into operative relation to the rear part of the shoe 100 and pressure applied to the shoe in a manner which will presently be described; and then this holder is withdrawn and the other holder B moved into operative position and pressure applied to the shoe, the holders being of sufficient length so that the areas of the shoe upon which pressure is exerted by the respective holders overlap at the middle portion of the shoe. 105

Referring now more particularly to Figure 2, the manner in which the distensible members are mounted in the holders A and B will be described; and inasmuch as the mounting of each member in its holder is the same, only the mounting of the distensible member 75 in the holder A will be described in detail. 110

The sections 19, 21 of the holder, except the two end sections 21, each comprise a metallic shell open at both ends, the two end sections 21 being closed at their outer ends. In each section the top wall and the wall toward the shoe are cut away in the manner shown in Figure 1 with respect to the section 19; and inside each shell and forming a part of each section is a hollow lining member 77 of resilient material such as rubber. The wall of each lining member is partly cut away on the top and on the side toward the shoe to form a narrow slot in which the adjacent 115 120 125 130

portion of the edge and upturned margin of the sole may be received, with the adjacent portion of the bottom of the sole resting upon the upper surface 79 of the cut-off side wall 5 and the adjacent portion of the upper of the shoe resting against the cut-off surface 81 of the top wall.

In order to ensure that, when the thin rubber distensible member 75 is inflated, no part 10 of it shall tend to be forced in between the walls of the lining member and the adjacent portions of the shoe, the top wall of the lining member tapers downwardly to a thin edge 82, and the side wall adjacent to the sole 15 of the shoe tapers to a thin edge 85. The two walls thus have thin tapered ends which are forced tightly against the shoe when the distensible member 75 is inflated so that there can be no space between the walls and the 20 shoe into which adjacent portions of the distensible member might be forced. It will be understood that each section of the holder comprises a rubber lining member substantially like the member 77.

25 The distensible member 75 is in the form of a thin rubber tube closed at both ends and may be inflated, when desired, by forcing air through a tube 83 which leads through the metallic shell and the rubber lining member 30 of the section 19 into the distensible member. Any suitable mechanism, not shown, may be used for forcing air through the tube 83 to inflate the member 75 and for permitting air to escape through the tube to deflate 35 the member.

Referring briefly to the holder B, the distensible member 175 is mounted in the rubber lining members, one of which is shown at 177 in the same manner in which the distensible member 75 is mounted in the rubber lining members of the holder A. A tube 183, which corresponds to the tube 83 of the holder A leads into the distensible member 175. It should be particularly noted 45 that it is the rubber lining members of the sections of the holders which contact with the shoe when the holders are closed about the ends of the shoe and that, since these lining members are resilient, they will conform substantially to the curves of the 50 portions of the shoe with which they contact.

In the operation of the machine the shoe is placed upon the pins 17 of the block 13 and 55 located properly as to its height above the table and as to its position substantially midway between the holders by adjusting the position of the rod 9 and the block 13. One of the holders, for example the holder A, is 60 caused to contact with the rear end of the shoe and to close about the sides of the shoe so as to occupy the position shown in the figures. Air under pressure is admitted to the member 75 to distend it, as shown, and 65 thereby press the upturned margin of the sole

against the foxing. Air is then permitted to escape from the distensible member, the holder A withdrawn and the holder B moved into contact with the forepart of the shoe, the member 175 first distended and then permitted to contact, and the holder B withdrawn. The upturned margin of the sole, and particularly the extreme upper portion of the margin along the edge, is thus pressed into firm contact with the foxing so that an 70 unbroken joint between the margin of the sole and the foxing will result from the subsequent vulcanization.

75 Although the invention has been set forth as embodied in a machine for pressing the upturned margin of the sole into place it should be understood that the invention is not limited in the scope of its application neither to the particular machine which has been shown nor the pressing of any particular part 80 of a shoe.

Having thus described my invention, what I claim as new and desire to secure by Letters Patent of the United States is:

1. A machine for applying pressure to a 90 shoe having, in combination, a sectional holder, flexible means for fastening the sections together, and a distensible member mounted in the holder.

2. A machine for applying pressure to a 95 shoe having, in combination, a substantially U-shaped sectional holder, flexible means for fastening the sections together, a distensible member mounted in the holder, and means for distending the member.

3. A machine for applying pressure to a 100 shoe having, in combination, a sectional holder each section comprising an outer rigid member and a resilient lining member, means for fastening the sections together, a distensible member mounted in the holder, and means for distending the distensible member.

4. A machine for applying pressure to a 105 shoe having, in combination, a substantially U-shaped sectional holder each section comprising an outer rigid member and a resilient lining member, means for fastening the sections together, a distensible member mounted in the holder, and means for distending the distensible member.

5. A machine for applying pressure to a 110 shoe having, in combination, a sectional holder each section comprising an outer rigid member and a resilient lining member, flexible means for fastening the sections together, 115 a distensible member mounted in the holder, and means for distending the distensible member.

6. A machine for applying pressure to a 120 shoe having, in combination, a substantially U-shaped holder having an elongated chamber therein one wall of which is made of resilient material and an elongated distensible member located in the chamber.

7. A machine for applying pressure to a 125

shoe having, in combination, a substantially U-shaped holder having an elongated chamber therein one wall of which is made of resilient material, said wall having a slot to receive the edge of the sole of the shoe, and an elongated distensible member located in the chamber.

8. A machine for applying pressure to a shoe having, in combination, a substantially U-shaped sectional holder, flexible means for fastening the sections together, a distensible member mounted in the holder, means for moving the holder to cause the holder first to contact with an end of a shoe and then to close about the sides of the shoe, and means for forcing fluid into the distensible member.

9. A machine for applying pressure to a shoe having, in combination, two sectional substantially U-shaped holders, flexible means for fastening the sections of each holder together, a distensible tubular member in each holder, means for alternately moving the sections into contact with and closing them about portions of a shoe, and means for distending the members.

10. A machine for applying pressure to a shoe having, in combination, two substantially U-shaped holders, a distensible member mounted in each holder, means for moving one of the holders into operative relation to one end and adjacent side portions of a shoe, means for forcing fluid into the distensible member of that holder, means for thereafter withdrawing that holder and for moving the other holder into operative relation to the other end and adjacent side portions of the shoe, and means for forcing fluid into the distensible member of said other holder.

11. A machine for applying pressure to a shoe having, in combination, two substantially U-shaped holders, a distensible member mounted in each holder, means for moving one of the holders into operative relation to one end and adjacent side portions of a shoe, means for forcing fluid into the distensible member of that holder, means for thereafter withdrawing that holder and for moving the other holder into operative relation to the other end and adjacent side portions of the shoe, and means for forcing fluid into the distensible member of said other holder, the holders being of such length that the areas upon which pressure is exerted overlap intermediate the ends of the shoe.

12. A machine for pressing the upper edge of the upturned margin of a rubber sole against the sides of a shoe having, in combination, a holder shaped to fit about a portion of a shoe and having a slot to receive the edge of the sole of the shoe, and a distensible member mounted in the holder.

13. A machine for pressing the upper edge of the upturned margin of a rubber sole against the sides of a shoe having, in combination, a holder shaped to fit about a por-

tion of a shoe and having a slot the walls of which are made of resilient material to receive the edge of the sole of the shoe, and a distensible member mounted in the holder.

14. A machine for applying pressure to a shoe along the lower edge thereof having, in combination, means for supporting the shoe, a plurality of distensible pressure-applying members, and means for moving them alternately into contact with the shoe.

15. A machine for applying pressure along the lower edge of a shoe having, in combination, a support for the shoe, a plurality of U-shaped distensible members, and means for moving each member bodily and at the same time causing it to close about the shoe.

16. A machine for pressing the upper edge of the upturned margin of a rubber sole against the sides of a shoe having, in combination, a sectional holder each section comprising a rigid shell, a resilient lining member having its walls cut away to provide a slot, the walls adjacent to the slot being tapered to thin edges, and a distensible member carried by the holder and adapted to act through the slots in the lining members.

17. A machine for applying pressure to a shoe having, in combination, two substantially U-shaped holders, a distensible member mounted in each holder in such manner that movement of the holders toward and from the shoe moves the distensible members, means for moving one of the holders with its distensible member into operative relation to one end and adjacent side portions of the shoe, means for forcing fluid into the distensible member of that holder, means for thereafter withdrawing that holder and member and for moving the other holder with its distensible member into operative relation to the other end and adjacent side portions of the shoe, and means for forcing fluid into the distensible member of said other holder.

In testimony whereof I have signed my name to this specification.
